UNITED STATES PATENT OFFICE.

EDWARD B. GARDNER, RALPH D. GARDNER, AND JOHN NIELSEN, OF BELOIT,
WISCONSIN.

GRINDING MACHINE.

Application filed August 18, 1924. Serial No. 732,602.

To all whom it may concern:

Be it known that we, EDWARD B. GARDNER, RALPH D. GARDNER, and JOHN NIELSEN, citizens of the United States, residing at 5 Beloit, in the county of Rock and State of Wisconsin, have invented certain new and useful Improvements in Grinding Machines, of which the following is a specification.

This invention pertains to grinding machines, and the present application is directed to improvements on the grinding machine structure shown and claimed in the co-pending application, Serial No. 648,217 filed June 28, 1923, by Ralph D. Gardner.

One of the primary purposes of our present invention is to provide a novel means for supporting the wheel dresser whereby the same may be swung back and forth in a plane parallel to the wheel face and in 20 a substantially horizontal plane.

Another object of the invention is to provide means for angularly adjusting the supporting links and the dresser tool relative to the adjacent face of the grinding wheel 25 whereby the dresser may be accurately aligned with the face of said wheel.

Another important object of our invention is to provide the dresser with hardened metal bearings for pivotal connection with 30 the supporting links and to provide for adjustment thereof and at the same time retain the dresser in a vertical plane centrally between opposed grinding discs whereby the face of either disc may be dressed.

Other objects and advantages of this invention will be apparent as the same becomes better understood by referring to the following description when considered with the accompanying drawings.

Referring to the drawings,

Fig. 1 is a rear elevation of a machine embodying our invention,

Fig. 2 is an end elevation looking toward the left at Fig. 1,

Fig. 3 is a side elevation of the dressing tool, one end thereof being shown in section,

Fig. 4 is a cross sectional view taken on line 4—4 of Fig. 3,

Fig. 5 is a transverse sectional view showing the pivotal connection between the dressing tool and one of the supporting links, and

Fig. 6 is a plan view of the dresser support showing the means for permitting the 55 angular adjustment thereof.

It will be observed by reference to the drawings, that the machine comprises a frame 5 having its upper face at each side of the center thereof shaped to provide guideways 6. The respective guideways 6 support reciprocating carriages 7 which are provided with suitable bearings in which the wheel carrying shafts 8 are respectively journaled. Upon the inner end of each shaft 8 is fixed a grinding wheel 9. These 65 shafts 8 may be driven through the medium of pulleys 19, or by individual motors.

The carriages 7 together with the grinding wheels 9 are moved toward and from each other by a suitable mechanism operated 70 through the medium of a rock shaft 11. This operating mechanism per se forms no part of the present invention and is fully shown and described in our co-pending application referred to above. It is sufficient 75 to state that the carriages 7 are normally urged toward each other to cause an approaching movement of the grinding wheels 9, by an arm 12 which is fixed to the rock shaft 11, the arm being actuated 80 by a weight 13 which is suspended therefrom. The rock shaft 11 is positively rocked in the opposite direction through the medium of a cam mechanism driven from the main drive shaft of the machine 14. The approaching movement of the grinding wheels is variably limited by a stop screw 15 which is carried by an arm 16 fixed to the rock shaft 11, said screw being set to engage an abutment shoulder 17 on the machine 90 frame.

For the purpose of dressing the opposed faces of the grinding wheels, we have mounted at the rear of the machine upon a bracket 16, the supporting plate 19. A 95 dresser tool 20 is pivotally supported on said plate by parallel links 21—21 so as to permit said tool to be moved radially of the grinding wheels and in a substantially horizontal plane.

The dressing tool 20 comprises a holder 22 and a cutter tool head 23, the latter being provided with a shank 24 which fits within a bore 25 extending inwardly from the end of the head 23. The tool head shank is adapted to be turned 180° about its longitudinal axis, and means are provided for retaining the tool in either extreme positions of adjustment. This means comprises diametrically opposed flats 26 formed on the 105 110

shank 24 and a set screw 27 mounted in the holder for engagement with either flat. Mounted in the holder 22 in advance of the bore 25 are a pair of spaced hardened metal bearings 28. These bearings 28 extend entirely across the holder, and the outer ends of each bearing are respectively formed with conical seats 29.

Each of the links 21 and their pivotal connections with the supporting plate 19 and the dressing tool 20 are identical and therefore the description of one link and its connections will suffice. Each link is in the nature of a swinging frame having at its lower end a pair of spaced depending bearing lugs 30—30 which are respectively connected to the plate 19 by means of pivot pins 31. The upper end of each link 21 is formed with upwardly extending bearing lugs 32—32 which form a resultant recess 33 for receiving the dressing tool 20. The bearing lugs 32 are respectively formed with transversely disposed bearing openings 34—34 which are, of course, arranged in alignment. Adjustably mounted in each of the bearing openings 34 is a bearing pin 35 having a tapering inner end 36 for engagement with the adjacent seat 29 of the associated bearing 28. These bearing pins 35 are adjustable longitudinally of the openings 34 and are adapted to be held in adjusted positions by set screws 32^a mounted in the bearing lugs 32. Thus, by means of these adjustable bearing pins 35 the pivotal connections between them and the dresser tool 20 may be adjusted to a nicety.

The supporting plate 19 and consequently the dresser tool 20 is mounted upon the bracket 18 for angular and longitudinal 40 adjustments relative to the face of the grinding wheel so as to make it possible for the operator to properly align the tool with the face. To this end we have provided the bracket 18 with a fulcrum pin 37 which projects upwardly into a slot 37^a formed in the plate 19. A pair of bolts 38 also project upwardly from the bracket through slots 39, formed in the plate 19. These slots 39 may be arcuate or, if straight 50 as shown in Figure 6, should be wide enough to loosely accommodate the bolts 38 therethrough so that the plate 19 may be adjusted to the angular relation desired. The bracket is also provided with a pair of upwardly extending lugs 40—40, and each lug is equipped with an adjustable screw 41 which bears against the adjacent face of the plate 19. When adjustment of the dresser tool is required the bolts 38 are loosened, whereupon by turning the screws 41 in the proper directions, the dresser tool together with supporting links may be swung in a horizontal plane about the fulcrum pin 37 or moved longitudinally 55 with respect to the wheels, or both, to prop-

erly align the tool with the faces of the grinding wheels, as desired. After this adjustment has been made, the bolts 38 are tightened to lock the dresser tool in its adjusted position. It should be noted that these adjustments are merely coarse adjustments to approximately position the dresser centrally between the grinding wheels and that finer adjustment is taken care of by moving the grinding wheels individually 75 toward the dresser when the bracket 18 is locked.

In operation, the dresser tool head is first adjusted about its axis so as to co-operate with the face of one of the grinding wheels. 80 The tool is then lined up with said grinding wheel face, and the operator, by grasping the outer end of the tool holder 22, swings the dresser tool back and forth radially of the wheel and in engagement therewith, the movement of the tool being in a substantially horizontal plane which preferably intersects the axis of the wheels. After one wheel has been surfaced, the operator then oscillates the tool head about an arc of 180°, 90 secures the same in position by the set screw 27, and then moves the dresser tool back and forth across the face of the other wheel.

We claim:

1. In a grinding machine, the combination with a rotary grinding wheel, of a support located at one side of the axis of said wheel, a tool for surfacing one face of said wheel, and a pair of parallel links respectively pivoted to said support and tool for permitting the tool to be moved substantially radially of the wheel. 95

2. In a grinding machine, the combination with spaced rotary grinding wheels, of a support located at one side of the axis of said wheels, a tool for surfacing the faces of said wheels, said tool being positioned between the wheels and comprising a holder and a tool head connected to the inner end of said holder, said connection between the tool head and the holder including means for permitting the oscillation of the tool about an arc of approximately 180°, means for securing said tool head to the holder in either extreme position of adjustment, and means for pivotally mounting said tool on said support for permitting said tool to be moved substantially radially of the wheels. 105

3. In a grinding machine, the combination with spaced rotary grinding wheels, of a support located at one side of the axis of said wheels, a tool for surfacing the faces of said wheels, said tool being positioned between the wheels and comprising a holder and a tool head connected to the inner end of said holder, said connection between the tool head and the holder including means for permitting the oscillation of the tool about an arc of approximately 180°, means for securing said tool head to the holder in 115 120 125 130

either extreme position of adjustment, and a pair of parallel links respectively pivoted to said support and tool for permitting said tool to be moved substantially radially of the wheels.

4. In a grinding machine, the combination with a rotary grinding wheel, of a support located at one side of the axis of said wheel, a tool for surfacing one face of said wheel, 10 said tool comprising a holder having a bore extending inwardly from the inner end thereof and a tool head having a shank mounted in said bore, a pair of spaced metal bearings extending transversely of the holder in advance of the shank, and a pair of parallel links respectively pivoted to said support and to the metal bearings of said holder for permitting the tool to be moved substantially radially of the wheel.

15 5. In a grinding machine, the combination with a rotary grinding wheel, of a support located at one side of the axis of said wheel, a tool for surfacing one face of said wheel, said tool comprising a holder having a bore extending inwardly from the inner end thereof and a tool head having a shank mounted in said bore, a pair of spaced metal bearings extending transversely of the holder in advance of the shank, and a pair 20 of parallel links respectively pivoted to said support and to the metal bearings of said holder for permitting the tool to be moved substantially radially of the wheel, the pivotal connection between each link and the 25 holder comprising a pair of spaced bearing pins carried by the link and engageable with the respective ends of the associated metal bearing.

6. In a grinding machine, the combination 30 with a rotary grinding wheel, of a support located at one side of the axis of said wheel, a tool for surfacing one face of said wheel, said tool comprising a holder having a bore extending inwardly from the inner end 35 thereof and a tool head having a shank mounted in said bore, and a pair of parallel links respectively pivoted to said support and to the metal bearings of said holder for permitting the tool to be moved substantially 40 radially of the wheel, the pivotal connection between each link and the holder comprising

a pair of spaced bearing pins carried by the link and engageable with the respective ends of the associated metal bearing, said bearing pins being laterally adjustable, and means 55 carried by the link for securing said pins in adjusted position.

7. In a grinding machine, the combination with a rotary grinding wheel, of a support located at one side of the axis of said wheel, 60 a pair of spaced links pivoted to the support for rocking movements towards and from the axis of said wheel, the upper end of each link being recessed to form resultant spaced lugs, a tool located within the recesses of said links, and means for pivotally connecting said tool to the spaced lugs of each link, whereby said tool may be moved substantially radially of the wheel to surface 65 the adjacent face of said wheel.

8. In a grinding machine, the combination with a rotary grinding wheel, of a support located at one side of the axis of said wheel, a pair of spaced links pivoted to the support for rocking movements towards and from the 70 axis of said wheel, the upper end of each link being recessed to form resultant spaced lugs, a tool located within the recesses of said links, and means for pivotally connecting said tool to the spaced lugs of each link, 75 whereby said tool may be moved substantially radially of the wheel to surface the adjacent face of said wheel, said pivotal connection between the tool and each link comprising a transversely disposed metal 80 bearing carried by the holder and bearing pins respectively carried by the lugs of the associated link and having means to adjust said pins.

9. In a grinding machine, the combination 90 with a rotary grinding wheel, of a support located at one side of the axis of said wheel, a tool for surfacing one face of said wheel, a pair of parallel links respectively pivoted to said support and tool for permitting the 95 tool to be moved substantially radially of the wheel, and means for angularly adjusting said support relative to the plane of the grinding wheel.
